CLAIM

The ornamental design for a camera, as shown and described.

DESCRIPTION

FIG. 1 is a front elevation view of a camera showing our new design with an environmental image of a fragmentary human hand and a handheld portion disclosed in broken lines;

FIG. 2 is a top and rear perspective view thereof, shown with the handheld portion omitted for ease of illustration; and, FIG. 3 is a top and front perspective view thereof.

The broken lines depict portions of the camera in which the design is embodied that form no part of the claimed design. The broken lines showing a human hand in FIG. 1 represent environmental structure and form no part of the claimed design. Additionally, the dash-dot lines denote the boundary of the claim and form no part of the claimed design.
